UNITED STATES PATENT OFFICE.

CARL SCHAUM, OF PHILADELPHIA, PENNSYLVANIA.

GOLF OR PUTTING CUP.

Application filed January 15, 1927. Serial No. 161,392.

My invention relates to an improvement in putting or golf cups and has for one of its objects the provision of a cup of improved construction whereby the flag socket 5 can be entered very easily and readily and in which a good support is provided for holding the flag socket vertically at all times.

A still further object of my invention is the provision of a device of the character indicated which will be simple and inexpensive to manufacture and in which good drainage is assured.

In the accompanying drawings, wherein I have illustrated an embodiment of my invention,

Fig. 1 shows the same in sectional elevation, while

Fig. 2 is a section on the line 2—2 of Fig. 1.

Referring to the drawings in detail, 1 designates the side walls of my improved cup, and 2 a conical bottom therefor. The walls and bottom may be a single casting as shown or in two pieces, just as desired. At the center of the conical bottom 2 I provide a flag socket aperture or opening 4. On the underside of the conical bottom 3 are four flat legs designated 5, these legs being spaced from each other as illustrated in Fig. 2, and the planes of the legs being radial to the aperture or opening 4 in the cup bottom. The inner edge of each leg extends inwardly toward the center of the conical bottom 3 beyond the edge of the hole or opening 4 as indicated at 6.

The lower ends of the legs 5 carry a base 7 of smaller diameter than the cup and also provided with a hole or opening 8, in line with the opening 4 in the cup bottom 3.

The socket for receiving a flag stick is designated 9, and as will appear from the drawing is provided with a collar 10 which engages the inwardly projecting portions of the legs 5 to limit the downward movement 45 of the socket relatively to the cup, it being understood that the portion of the socket below the collar 10 passes through the opening 4 in the bottom of the cup and down through the hole 8 in the base member 7 of the cup and into the ground, as indicated at 50 11. The opening 4 in the cup bottom is larger in diameter than the collar 10, but the legs 5 extend inwardly beyond the edge of this opening a sufficient distance to provide 55 a support for the collar, as above noted, thereby leaving a drainage space about the

periphery of the collar 10, preventing the collar from acting as a valve and enabling water to drain freely out of the cup down through the opening 4, between the legs 5 60 and into the ground.

It will be apparent from the foregoing that I have provided a device for the purpose above indicated in which good drainage is assured at all times by the conical construction of the cup bottom 3 and the opening 4 therein taken in conjunction with the spaced legs 5.

It will be apparent, furthermore, that, due to the conical bottom of the cup, the opening 4 and legs 5, together with the base member 7, enable the flag socket to be placed readily in position and properly held in such position.

It will be obvious also that the base 7, 75 being of smaller diameter than the cup walls, water draining out of the cup is free to pass outwardly between the legs 5 and over the edge of the base 7 and into the ground.

What I claim is:

1. A cup for golf, comprising a body portion, a bottom for said body portion provided with a central aperture, a base for said cup, said base being provided with an aperture in line with the aperture in the cup bottom, legs spacing the cup bottom and base from each other and uniting said cup bottom and base, the inner edge of each leg projecting inwardly beyond the edge of said apertures.

2. A cup for golf comprising a body portion, a bottom provided with an aperture, a base, legs spacing the base and cup bottom from each other, said legs being spaced about the said aperture with their planes extending radially thereof, the inner edge of each leg projecting inwardly beyond the edge of said aperture.

3. A cup for golf, comprising a body portion, a bottom for said body portion provided with an aperture, a base, legs uniting said base and cup bottom, said base lying below the bottom of said walls of the body portion of the cup and being provided with an aperture in vertical alignment with the aperture in the cup bottom, said legs being spaced from each other to permit of drainage of the cup through the aperture in the cup bottom and laterally with respect to the cup.

4. A cup for golf comprising a body portion, a conical bottom, said bottom having

an aperture extending vertically of the cup at the apex of the cone, a base member lying beneath said bottom and having an aperture in line with the aperture in the cup bottom, 5 legs uniting the base and cup bottom, said legs being spaced from each other about said apertures and having their inner edges projecting slightly beyond the aperture in the cup bottom.

10 5. A cup for golf comprising a body portion, a bottom having an aperture at the center thereof, a base of smaller diameter than said bottom provided with an aperture lying beneath the aperture in the cup bottom, a 15 plurality of legs spacing the cup bottom and base from each other, said legs being flat with their planes radially disposed with relation to said apertures, the inner edge of each leg projecting slightly beyond the edge 20 of the aperture in the cup bottom.

6. In combination, a golf cup comprising

a bottom having an aperture, a base, legs spacing the cup bottom and base, the inner edges of said base projecting inwardly slightly beyond the edge of the aperture in 25 the cup bottom, a flag socket, adapted to be received by said aperture and to pass between said legs, and a collar or abutment provided on said socket adapted to engage the upper edge of said legs, said collar being 30 of less diameter than the aperture in the cup bottom.

7. A cup for golf comprising a body portion, an unobstructed bottom for said body portion, a base beneath the cup bottom and spaced therefrom, means being provided for permitting of drainage of the cup laterally 35 in the space between the cup bottom and base.

This specification signed this 10 day of January, 1927.

CARL SCHAUM.
